ATT'Y.

UNITED STATES PATENT OFFICE.

HENRY H. CURTIS, OF NORTH ATTLEBOROUGH, MASSACHUSETTS.

DESIGN FOR A HANDLE FOR SPOONS, &c.

SPECIFICATION forming part of Design No. 28,408, dated March 29, 1898.

Application filed February 26, 1898. Serial No. 671,859. Term of patent 7 years.

To all whom it may concern:

Be it known that I, HENRY H. CURTIS, residing in North Attleborough, in the county of Bristol and State of Massachusetts, have invented and produced a new and original Design for the Handles of Spoons, Forks, and Similar Articles, of which the following is a specification, reference being had to the accompanying drawing, forming part thereof.

○ The drawing is a plan view of a spoon, showing my new design.

The broken lines indicate a fork in which the design is embodied.

As represented in the drawing, the leading or material features of my design consist in the curved outline of the handle bounded by a series of marginal balls or beads, a foliated crest with pendent chrysanthemums, and a floral cluster intermediate the blade and stem of the handle.

In the drawing, A is the stem, and B the blade, of the handle. From a point near its base *q* the stem gradually expands, forming two slight swells *a a*. The resulting depressions in outline *b b* mark the upper limit of the stem A and embrace a spray of chrysanthemums *c*. The outline of the blade has corresponding swells *d d*, somewhat more pro-

nounced, merging in the final swells *ss*, which are more pronounced than the preceding and contribute a generally circular appearance to the end of the handle. Two conveying foliations *ll* at the end of the blade embrace a ball *n* and are supported by the larger pair of diverging foliates *ff*, which terminate in the beading. The crest of the blade is completed by a bunch of chrysanthemums *m*, triangular in general contour, intermediate and pendent from the crest foliations. Following the outline of the handle throughout, beginning at the bases of the foliates *ll*, are series of balls or beads *oo*, gradually diminishing in size as the lower end of the stem is approached.

Having thus described my invention, what I claim as new, and desire to secure by Letters Patent, is—

The design for the handle of a spoon, fork, or similar article, herein shown and described.

In witness whereof I have hereunto set my hand.

H. H. CURTIS.
